Term of patent 7 years

(Cl. D74—17)

Fig. 1

Fig. 2

To all whom it may concern:

Be it known that I, Norman Zabilansky, a citizen of the United States, residing at Staffordville, State of Connecticut, have invented a new, original, and ornamental Design for a Fountain Pen, of which the following is a specification, reference being had to the accompanying drawing, forming a part hereof.

Fig. 1 is a side view, slightly in perspective, of a fountain pen showing my new design; and

Fig. 2 is a view of the pen, when positioned substantially as shown in Fig. 1, taken from above at an acute angle to the vertical.

I claim:

The ornamental design for a fountain pen, as shown.
